APPARATUS FOR TEEMING OF MOLTEN METALS

George C. Bahm, 354 Austin Drive, Fairless Hills, Pa.
Filed May 8, 1963, Ser. No. 278,818

5 Claims. (Cl. 22—34)

This invention relates to the teeming of molten metals.

The practice for over seventy-five years has been to employ an internal stopper rod assembly for the teeming of molten metals from a refractory lined ladle into molds where the metal cools to solidification and for further processing. The stopper rod has a special head which seats at the upper end of a nozzle mounted in a nozzle plate carried in the bottom of the ladle. At the top of the steel rod a gooseneck is attached to which a stopper rod lifting assembly is connected, this in turn being controlled by an operating lever assembly exteriorly disposed with respect to the ladle. With this structure the rod is raised or lowered thereby opening or closing the nozzle and permitting the molten or liquid metal to pass through the nozzle into the mold.

It is the principal object of the present invention to provide apparatus for the teeming of molten metal which is simple in construction and requires substantially fewer parts than structures presently used or heretofore proposed.

It is a further object of the present invention to provide improved apparatus for the teeming of molten metal which can be quickly and easily installed on ladles now in use.

It is a further object of the present invention to provide improved apparatus for the teeming of molten metal which in one form can be mounted on the ladle from the inside and which in another form can be mounted on the ladle from the outside depending upon the specific ladle construction which is employed.

It is a further object of the present invention to provide improved apparatus for the teeming of molten metal which is expendable and is quickly replaced if desired or required for a new heat.

It is a further object of the present invention to provide improved apparatus for the teeming of molten metal which can be manually or power operated as desired.

It is a further object of the present invention to provide improved apparatus for the teeming of molten metal which is not adversely affected at the temperatures and forces applied thereon in use.

Other objects and advantageous features of the invention will be apparent from the description and claims.

The nature and characteristic features of the invention will be more readily understood from the following description taken in connection with the accompanying drawings forming part thereof, in which:

FIGURE 1 is a fragmentary vertical sectional view of a ladle having one form of teeming apparatus in accordance with the invention mounted thereon;

FIG. 2 is an enlarged vertical central sectional view of the teeming apparatus shown in FIG. 1 removed from the ladle;

FIG. 3 is a bottom plan view of the apparatus shown in FIG. 2;

FIG. 4 is an exploded perspective view showing one type of actuation; and

FIG. 5 is a view similar to FIG. 2 showing another form of teeming apparatus in accordance with the invention.

It should, of course, be understood that the description and drawings herein are illustrative merely and that various modifications and changes can be made in the structure disclosed without departing from the spirit of the invention.

2

Like numerals refer to like parts throughout the several views.

Referring now more particularly to FIG. 1 of the drawings a ladle tank 10 is shown having a bottom nozzle plate 11 and a ceramic refractory lining 12. The bottom plate 11 has an opening 15 and refractory lining 12 has an opening 16 axially aligned with the opening 15.

Referring now more particularly to FIGS. 2, 3 and 4 of the drawings, the form of teeming apparatus of the present invention for insertion from the interior of the ladle tank 10 preferably includes a jacket 18 which can be and preferably is of metal, with a hollow cylindrical side wall 19 having an inner face 20, and a bottom wall 22 with a top face 23, a bottom face 24 and a central opening 25 therein between the top and bottom faces 23 and 24.

The bottom wall 22 rests on and is supported by the bottom plate 11 and is provided with a plurality of studs 26 which extend downwardly from the bottom face 24 and through the bottom plate 11. The studs 26 are held in place by nuts 27 thereon. In use rammed refractory clay 28 is provided to fill the space between the exterior of the wall 19 and the opening 16.

Within the jacket 18 a cap 30 is provided, which may be of ceramic refractory material having a hollow cylindrical wall 31 engaging the inner face 20 of the side wall 19 and resting on and being supported by the top face 23 of the bottom wall 22. The cap 30 also has an integral top wall 32 preferably with a slightly dished upper face 33 and a flat lower face 34. A port opening 35 is provided preferably offset from the vertical central axis of the cap 30.

The cap 30, in the interior thereof, is provided with a core or spindle 37, preferably of ceramic refractory material, having an upper portion 38 of cylindrical shape in horizontal cross section with an outer vertical face 39, a cylindrical downward extension 40 of reduced diameter with an outer face 41 and which extends through the opening 15 and below the bottom plate 11, and a lower operating extension 42 shown as having a hexagonal exterior 43. The upper portion 38 has the outer side face 39 thereof rotatable within the cylindrical wall 31, has a flat upper face 45 engaging the flat lower face 34 of the cap 30 and has a lower shoulder 46.

The core or spindle 37 has extending vertically therethrough a port 47 in offset relation to the vertical central axis thereof. The port 47 is adapted upon turning of the core or spindle 37 to be moved into alignment with the port opening 35 or out of alignment therewith.

In the space between the shoulder 46, the face 41, and the top face 23 of the jacket 26, a thrust bearing ring 48 is provided which may also be of ceramic refractory material containing a suitable lubricating component such as graphite.

In the form of the invention shown in FIG. 5 the construction is the same as that previously described, except that the outer face of the jacket 18' is frustoconical and complementary to a frustoconical opening 16' in the bottom refractory lining 12, and has studs 50 which are held in a mounting ring 51 by nuts 52 on the studs 50. The mounting ring 51 is carried on studs 53 on the bottom plate 11 and held in place by nuts 54 on the studs 53.

An operating lever 55 engageable with the hexagonal exterior 43 permits of turning of the spindle 37 as desired.

The mode of use will now be pointed out. Assuming that the ladle tank 10 has a charge of molten metal therein which is to be delivered into a mold or other desired location the ladle tank 10 is moved to the delivery location.

The operating lever 55, engaged with the hexagonal exterior 43 of the spindle 37 is swung in a horizontal plane manually or with any desired mechanical operator

to bring the port 47 into alignment with the port opening 35. A controlled teeming is thus made available.

At any time it is desired to shut off the flow of molten metal the lever 55 is moved to turn the port 47 to a position out of alignment with the port opening 35.

Leakage of molten metal is obviated by reason of the relation of the jacket 18 or 18', cap 30 and spindle 37.

It will also be noted that the apparatus of the present invention can be readily installed from the interior of the ladle tank 10 as in FIGS. 1, 2 and 3 or from the exterior, as in FIG. 5.

I claim:

1. Teeming apparatus for use with the bottom wall of a ladle tank having an upper face comprising a cap having a top wall flush with said upper face and a side wall extending downwardly from said top wall, said cap having a vertical port in said top wall, a spindle rotatably mounted within said cap on a vertical rotational axis with its top extremity beneath said top wall and surrounded by said side wall, said spindle having a horizontally disposed supporting shoulder intermediate its top and bottom extremities, a supporting bearing beneath said shoulder, said spindle having an operating portion extending downwardly below said bottom wall, and said spindle having a vertically extending port therein normally in offset relation to said vertical port and movable into alignment therewith.

2. Teeming apparatus as defined in claim 1 in which a jacket is provided in surrounding relation to said cap, said jacket has a cylindrical outer face, and said jacket is assembled to said bottom wall of said ladle tank from above.

3. Teeming apparatus as defined in claim 2 in which said jacket is surrounded by a ring of refractory.

4. Teeming apparatus as defined in claim 1 in which the bottom wall of the tank has a refractory lining with a frustoconical opening wider at the bottom, a jacket is

provided in surrounding relation to said cap, said jacket is frustoconical and complementary to said opening and insertable from below, a mounting ring is provided upon which said jacket is carried, and members are provided securing said mounting ring to said bottom wall of said ladle tank.

5. Teeming apparatus for molten metal and for assembly to the bottom wall of a ladle tank having an upper face comprising a jacket having a vertical cylindrical wall, a cylindrical cap within and surrounded by said jacket having a top wall flush with said upper face and a side wall engaging and extending downwardly within said jacket, said cap top wall having a vertical port opening therethrough offset from the center thereof, a cylindrical spindle rotatably mounted within said cap on a vertical rotational axis with its top extremity beneath and in engagement with said top wall and surrounded by said side wall, said spindle having a vertical port offset from the vertical central axis thereof normally out of alignment with said vertical port opening and movable into alignment therewith, said spindle having an upper portion terminating at a shoulder and a downward operating extension therefrom, and a supporting bearing beneath said shoulder.
